UNITED STATES PATENT OFFICE.

ALVA PUTMAN JOHNSON, OF TULIA, TEXAS.

WRENCH.

1,084,441.

Specification of Letters Patent. Patented Jan. 13, 1914.

Application filed August 7, 1913. Serial No. 783,563.

To all whom it may concern:

Be it known that I, ALVA PUTMAN JOHNSON, a citizen of the United States, residing at Tulia, in the county of Swisher and State of Texas, have invented certain new and useful Improvements in Wrenches, of which the following is a specification.

My invention relates to an improvement in wrenches, and the object is to provide a handle having a resilient head which head is provided with a socket in which a ratchet is received, the ratchet being engaged by the resilient head for turning the nut.

The invention consists of still other novel features of construction and combinations of parts which will be hereinafter described and pointed out in the claim.

In the accompanying drawings: Figure 1 is a view in side elevation; Fig. 2 is a view in elevation of the head of the wrench with one of the side plates removed; Fig. 3 is a cross sectional view through the head.

A represents the handle, which is provided with a resilient head 1 at each end thereof. The heads are preferably made circular in form, one end being free, and a pawl 2 is formed on the inner surface of the end of the head, which is adapted to engage the teeth of the ratchet 3, which is fitted within the socket 4 formed in the head. The ratchet 3 is held within the socket 4 by means of disks 5, 5, one on either side, said disks and ratchet being held together by rivets 6, 6, and the disks having angular openings 7, 7, corresponding and registering with a corresponding opening through

the center of the ratchet to receive the nut or bolt to be held or turned.

The operation of the wrench is simple. It is applied over the nut or bolt to be turned in the usual manner of a wrench, the pawl 2 forming the handle to swing freely in one direction while it rides over the teeth of the ratchet and acting to lock the ratchet to the head when turned in the opposite direction to screw the nut on the bolt.

Having fully described my invention, what I claim as new and desire to secure by Letters Patent is—

As an article of manufacture, a wrench comprising a handle and a resilient head integral therewith and bent approximately into circular form and terminating at its free end in an inwardly extending pawl, a ratchet housed within the circular head, the teeth of which are engaged by the pawl on the head to lock the ratchet to the head when turned in one direction and permit the head to turn upon it when moved in the opposite direction, disks embracing the opposite sides of the ratchet and head and secured to the ratchet to hold the latter within the head, said disks and ratchet having a central opening to receive the nut or bolt to be held or turned.

In testimony whereof I affix my signature in the presence of two witnesses.

ALVA PUTMAN JOHNSON.
